UNITED STATES PATENT OFFICE.

HENRY M. SHEER, OF QUINCY, ILLINOIS.

HEATER FOR INCUBATORS.

1,392,709.

Specification of Letters Patent.

Patented Oct. 4, 1921.

Application filed July 10, 1920. Serial No. 395,422.

To all whom it may concern:

Be it known that I, HENRY M. SHEER, a citizen of the United States, residing at Quincy, in the county of Adams and State 5 of Illinois, have invented certain new and useful Improvements in Heaters for Incubators, of which the following is a specification.

My invention relates to an improvement 10 in heaters for incubators.

The fundamental features of the present invention are to enable the operator to handle the burner without being obliged to manipulate the entire lamp, which has been 15 necessary hitherto, since that method presented difficulties in making connections with the regulator and automatic oil control, and every time the lamp was given attention the adjustment of the regulator was necessarily 20 disturbed. With my present construction, the relative position of the oil font and the regulator, both of which are fixed, remains the same, regardless of any attention given 25 the burner or change in the position of the same.

This invention therefore includes an oil font and regulator stationarily placed, a burner, a valve controlled by the regulator to automatically determine the supply of oil 30 to the burner, and an oil feed pipe for conducting the oil from the valve to the burner made in two parts, so that the burner can be moved quite independently of the oil font, regulator, valve and the lamp, thus making 35 it entirely unnecessary to disturb the oil font and regulator, while at the same time making the adjustment of the burner a simple and independent feature.

In the accompanying drawings:

40 Figure 1 is a view in perspective showing the burner in one position; and

Fig. 2 is a similar view showing the burner lowered and swung to one side.

A, represents an incubator of any approved type, and the numeral 1 is the oil font, preferably stationed permanently on top of the incubator, as shown in Figs. 1 and 2. A pipe leading from the font leads to the valve 2, and this valve is controlled by a thermostatic regulator 3 which is supported by a tube 4 of suitable length and extending the required distance, preferably from the top of the incubator in to a point in proximity to the eggs, where it is held by a clamping 50 plate 5 made of two parts and clamped

around the upper end of the tube 4 and held by screws or bolts permanently on the incubator. The usual rod 6 extends through this tube to the oil control lever 7, which extends to the valve 2 and controls the passage of oil therethrough. 60

A base 8 is fastened on the incubator in position to hold the valve 2 in place. From this base, the pipe which fits the burner extends. This pipe is made in two parts, the upper section 9 is preferably bent L-shaped, and extends from the base around the upper corner of the incubator with its free end extending downwardly, as shown in Fig. 2. The lower section 10 is adjustably supported 70 by the bracket 11, where it is held by two set-screws 12, which admit of its being raised and lowered and turned axially, as shown in Figs. 1 and 2. The lower end of this section 10 is bent horizontally and extends to 75 the burner 14 of the lamp 15.

The upper end of the pipe section 10 preferably has a cup or funnel 16 thereon, so that the oil coming down from the upper section 9 of the pipe is caught therein and 80 flows on down through the pipe section 10 of the burner. Thus the two sections 9 and 10 of the oil feed pipe telescope, the lower end of the upper section into the upper end of the lower section 11. 85

With this arrangement, it is perfectly convenient by simply loosening the set-screws 12 to adjust the burner either to raise or lower or swing the latter aside, as shown in Fig. 2, when it is necessary to give attention 90 thereto. Thus it will be seen that the oil font 1, the regulator 3, and the lamp 15 are never disturbed the slightest degree, the burner only being adjustable, this being rendered possible by making the feed pipe in 95 two sections 9 and 10, with the latter (which supplies the burner 14 directly) vertically and axially adjustable.

Obviously the oil font or container might be fastened against the end or side of the 100 incubator instead of on top, and the tube 4 of the regulator might enter the incubator from the end or side, although the form illustrated has been found satisfactory, and is probably preferable. It is also understood 105 that the length of the tube 4 and the rod 6 would be subject to variation according to the size or type of incubator. In fact many other changes might be made without departing from the spirit and scope of my in- 110

vention, the illustrated form being intended to represent a type more than an exact form of the invention.

I claim:

- 5 1. A heater for incubators including an oil feed pipe made in at least two parts or sections, one of which feeds into the other, an oil font, valve and regulator in fixed relation to one pipe section, the other section of oil feed pipe adjustable lengthwise and axially, and a burner connected thereto.
- 10 2. The combination with a suitable support, of an oil font, a regulator, a valve secured in an oil supply pipe, the latter made in two sections, one of which sections together with the oil font, valve and regulator are in fixed relation to each other upon the support, the other section of the oil feed pipe adjustable, and a burner to which the 15 adjustable feed pipe section leads.
- 20 3. The combination with an incubator, an oil container, a valve, a valve regulator connected therewith, of an oil feed pipe made in sections, one of which is fixed to the in-

cubator and the other adjustably connected therewith in position to receive oil from the fixed pipe section, and a burner connected with the adjustable pipe section.

4. The combination with an incubator, an oil container, valve, and regulator supported thereon, of a base, an oil supply pipe made in two sections, one of which is secured to the base, and the other section telescopically connected with the fixed section and adjustably supported both endwise and 35 axially, and a burner connected with the adjustable section.

5. The combination with an incubator, of an oil font, regulator and valve secured thereto, a burner, an oil feed pipe made in 40 sections, one of which is adjustably connected to the burner and detachably connected with the incubator, and the other pipe section fixed to the incubator and discharging into the adjustable pipe section. 45

In testimony whereof I affix my signature.

HENRY M. SHEER.
